SPRINKLING APPARATUS

Walter H. Coles and Bert J. Nelson, Troy, Ohio,
assignors to The Skinner Irrigation Company,
Troy, Ohio, a corporation of Ohio

Application April 3, 1939, Serial No. 265,636

5 Claims. (Cl. 299—69)

This invention relates to water distributing or sprinkling devices and more particularly to sprinklers having a rotatable sprinkling nozzle.

One object of the invention is the provision of a sprinkling device in which the rotational movement of a distributing nozzle is controlled by the conjoint action of a reaction force produced by a reaction stream and an impact device which taps or strikes the rotatable sprinkler head to impart a step by step rotative force thereto.

Another object of the invention is the provision of a sprinkling device having a main distributing nozzle for directing a stream substantially radially outwardly and at a suitable upward inclination, and having a reaction nozzle which directs a stream at an angle to the radial direction to apply a reaction force to the nozzle, the reaction nozzle being provided with a mechanical impact means operated by the stream coming from the reaction nozzle and imparting a step by step rotative force to the main nozzle.

Another object of the invention is the provision of a sprinkling device of the character mentioned having provisions for readily adjusting the direction of the reaction stream and the force of the impact blows.

Other objects and advantages of the invention will be apparent from the following description and the appended claims, taken in connection with the accompanying drawing.

In the drawing in which like characters of reference designate like parts throughout the several views thereof,

Fig. 1 is a top plan view of a sprinkling device embodying the present invention;

Fig. 2 is a side elevation of the sprinkling device, the central portion of the same being shown in vertical section;

Fig. 3 is a side elevation of the reaction nozzle and the impact mechanism, shown on an enlarged scale and with certain parts illustrated in section; and

Fig. 4 is a section on the line 4—4 of Fig. 3.

The sprinkler, which is illustrated as a preferred embodiment of the invention, comprises a sprinkler head 10 rotatably mounted on a suitable support 11 and having a main distributing nozzle 12 and an auxiliary nozzle 13 for sprinkling or watering the ground. The main distributing nozzle is provided at the outer end of an upwardly inclined pipe 14 and extends preferably radially outwardly and at a suitable upward inclination so as to throw the stream to a considerable distance. The auxiliary nozzle 13 is secured

on a reaction head 15 which is arranged on the outer end of a radially extending pipe 16.

The inner ends of the pipes 14 and 16 communicate with a supply chamber 17 to which the water is furnished through openings 18 in the shell 20, the latter forming an upward extension of the stationary support 11 which is provided with suitable threads 21 adapted to be secured to a water supply pipe or coupling.

The lower part of the sprinkler head 10 is formed by a nut 22 having a threaded upward extension 23 which is in threaded engagement with the upper part of the head as shown in Fig. 2. Inside of the nut 22 is a space 24 which receives the spring 25, upper and lower washers 26 and 27, and suitable packing 28. The upper washer 26 engages a flange 29 and the spring is provided between the washers so as to normally hold them apart and maintain the packing under sufficient force to prevent leakage from the water chamber 17. The upper end of the shell 20 is closed by its top wall 30. Two semi-circular rings 31 are received in a groove 32 provided at the upper end of the shell 20, the lower sides of these ring portions bearing against a metal plate 33 and the upper sides bearing against the cover plate 36, thus rotatably supporting the sprinkler head on the support 11. The plate 33 rests on a packing washer 34 which acts as a seal to prevent water from leaking upwardly around the shell 20. The upper side of the plate 33 is engaged by the removable top cover plate 36 which is connected to the top of the body portion of the sprinkler head by means of suitable attaching screws 37.

The stream which issues from the auxiliary or reaction nozzle 13 is preferably considerably smaller than that distributed from the main nozzle 12, and the reaction nozzle is adapted to be positioned adjustably so as to distribute the reaction stream at a desired angle to the radial direction in order that the reaction force can be readily changed to give a comparatively high speed of operation or a speed of rotation that may be as small as desired. The reaction head 15, as shown, is adjustably supported for rotational movement on the upper end of an elbow 38, preferably by screw threads, and is provided with a lug 39 which projects between two spaced arms 40 and 41 which extend from a collar 42 that is brazed or screwed to the elbow 38. The space between the arms 40 and 41 is considerably larger than the width of the lug 39 and permits adjustment of the axis of nozzle 13 from a position, in the vertical plane of the nozzle 12 to a wide angular position as shown in Fig. 1. The

two arms 40 and 41 are provided with the adjustable thumb screws 43 and 44 the inner ends of which bear against opposite sides of lug 39 and thus rigidly hold the reaction head 15 in the desired position on the elbow 38. The thumb screw 43 may be loosened and the thumb screw 44 tightened to turn the head 15 to decrease the effective component of the reaction force. By loosening screw 44 and tightening screw 43 the reaction force component may be increased.

The stream issuing from the reaction nozzle 13 operates a mechanical impact device which is arranged outside of the water passages in the sprinkler, and thus eliminates any interference that might be otherwise caused by excessive dirt in the water. This impact device imparts a step by step rotative movement to the sprinkler head serving to rotate the sprinkler head in the same direction of rotation as that due to the reaction force. It will thus be apparent that the direction of the reaction stream may be so adjusted as to give only a small or even negligible turning effect on the main sprinkler nozzle so that the rotative force on the sprinkler head will come principally from the impact device, giving a slow step by step movement, such as might give a speed of rotation of the order of 1 revolution in 15 minutes. However the speed of rotation may be made as fast as desired by suitable regulation of the rotative forces.

The impact device preferably comprises an impact arm 46 pivotally supported on a stud 47 which is fixed to the reaction head 15 and which projects upwardly preferably at a suitable angle 35 of inclination as shown in Fig. 3. One end of the arm projects rearwardly from the nozzle to form a counterweight portion 48, the forward end of the arm projecting over the nozzle and carrying a vane 49 which is normally urged to a position 40 in front of the reaction stream issuing from nozzle 13. The vane 49 is of generally triangular form, having diverging water engaging surfaces 50 and 51, each of which is shown with a lower flange 45 projection 54, the body portion of the vane being pivotally supported on a stud 52 which is threaded in the arm 46. A lug 53 carried by the arm 46 projects down substantially between the two ears 55 and 56 which limit the swinging movement of the vane on the stud so that either one or the other of the surfaces 50 or 51 may be arranged 50 substantially parallel to the axis of the nozzle 13.

In the normal position of the arm 46 as shown in Fig. 4, this arm engages a stop 58 provided on the reaction head 15, and is yieldingly urged 55 against this stop by means of a spring 59 one end of which engages the arm while the other end engages the fixed stud 47. As shown, the spring 59 is a spiral coil spring having one end bent inwardly and received in a notch or groove 60 provided in the stud 47 while the other end of the spring is turned outwardly as indicated at 61 and is received in a slot 62 provided in a spring enclosing ring 63 which is fixed to a cover plate 64. 60 A nut 65 threaded on the outer end of the stud 47 retains the cover plate 64 and the spring in position, with the ring 63 fitting in a cylindrical passage 65' provided in the hub portion of the arm 46. The spring tension may be adjusted by turning 65 the cover plate 64, and the cover is held in 70 adjusted position on the arm by means of a screw 66 the head of which overlaps and bears against the top of the peripheral portion of the cover plate 64. When the screw 66 is loosened, the 75 cover 64, which is preferably provided with a

knurled peripheral portion, may be turned to properly tension the spring so that it will return the arm from a displaced position into engagement with the stop 58 with a desired impact force.

The stream of water issuing from the reaction nozzle 13 strikes against the pivoted vane, and if the vane is in a centered position as indicated in Fig. 4, the vane is swung clockwise until the ear 53 strikes against the lug 53, since an outward deflecting projection 67 is provided at the outer 10 end of the surface 50. This applies the force of the water to the surface 51 and the arm 46 is therefore swung counterclockwise against the action of spring 59. The swinging movements of the arm are gradually stopped by the action of 15 the spring by the time the arm has turned about a quarter of a revolution or so from its normal position. The spring then acts to return the arm forcibly against the stop 58, and as the vane enters the stream again the force of the water 20 acting on the surface 50 of the vane momentarily adds to the force of the spring in producing a striking effect on the stop 58, although immediately after the stop is struck, the stream swings the arm out again, this action being repeated time 25 after time and each returning movement of the arm producing an impact serving to tap the sprinkler head and produce a step by step movement of the main distributing nozzle.

With rotatable sprinklers in which the rotative movements are produced entirely by reaction means, the resistance to turning may prevent the sprinkler from starting, especially where the reaction nozzle is arranged to give a slow speed of rotation, and sprinklers in which the rotational movements of a main distributing nozzle are given solely by impact means may require impact blows of considerable magnitude, especially where the sprinkler is of large size and throws a large stream of water to a considerable distance. However, as will now be apparent, the present invention provides a construction in which the impact means may be so arranged as to give comparatively small blows which when added to a small continuous turning force obtained from a reaction nozzle insure proper starting and give a very wide range of speeds of operation.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A sprinkler of the character described comprising a support, a sprinkler head rotatably mounted on said support, a main distributing nozzle on said head for projecting a stream angularly upwardly and substantially radially outwardly, an auxiliary distributing nozzle on said head for directing a stream at an angle to the radial direction to apply a reaction force to the head in a direction to rotate the head on the support, and an oscillatory mechanical impact lever pivotally carried by said auxiliary nozzle and having means operated by the stream from said auxiliary nozzle for swinging the lever, said lever having means for tapping the auxiliary nozzle at the end of its oscillatory movement in one direction to impart a step by step rotative force to the sprinkler head in the same direction as the reaction force of the auxiliary distributing nozzle.

2. A sprinkler of the character described com-

prising a support, a sprinkler head rotatably mounted on said support, a main distributing nozzle on said head for projecting a stream angularly upwardly and substantially radially outwardly, an auxiliary distributing nozzle on said head for directing a stream at an angle to the radial direction to apply a reaction force to the head in a direction to rotate the head on the support, means to vary the amount of the reaction force applied to the head, a mechanical impact means operated by the stream issuing from said auxiliary nozzle for tapping the sprinkler head to impart a step by step rotative force to the sprinkler head in the same direction as the reaction force of the auxiliary distributing nozzle.

3. A sprinkler of the character described comprising a support, a sprinkler head rotatably mounted on said support, a main distributing nozzle on said head for projecting a stream angularly upwardly and substantially radially outwardly, a reaction nozzle adjustably fixed on said head, adjustable means operable to determine the direction of distribution of the stream from the reaction nozzle to vary the amount of the reaction force on the head resulting therefrom, and a mechanical impact means carried by the reaction nozzle and operated by the stream issuing from the reaction nozzle for tapping the sprinkler head to impart a step by step rotative force to the sprinkler head in the same direction as the reaction force of the auxiliary distributing nozzle.

4. A sprinkler of the character described comprising a support, a sprinkler head rotatably

mounted on said support, a main distributing nozzle on said head for projecting a stream angularly upwardly and substantially radially outwardly, a reaction nozzle adjustably fixed on said head, adjustable means operable to vary the amount of the reaction force on the head resulting therefrom, and a mechanical impact means operated by the stream issuing from the reaction nozzle for tapping the sprinkler head to impart a step by step rotative force to the sprinkler head in the same direction as the reaction force of the auxiliary distributing nozzle.

5. A sprinkler of the character described comprising a support, a sprinkler head rotatably mounted on said support for movement about a substantially vertical axis, a main distributing nozzle fixed on said head for directing a stream angularly upwardly and substantially radially outwardly, an auxiliary reaction nozzle on said head for directing a stream at an angle to a radial direction to apply a reaction force to the head to urge the head rotatably on the support, means for adjusting said reaction nozzle to change the angularity of the reaction stream with respect to the radial direction, an oscillatable arm carried by said reaction nozzle, a vane on said arm and arranged to swing back and forth in front of the reaction nozzle, spring means for returning the arm to the stream, and means on said reaction nozzle impacted by said arm at the end of a swinging movement thereof to impart a step by step rotative force on the sprinkler head in the same direction as the reaction force resulting from the reaction nozzle.
